UNITED STATES PATENT OFFICE.

CHARLES MARTIN MALLORY, OF FLANDREAU, SOUTH DAKOTA.

WIRE-STITCHING MACHINE.

SPECIFICATION forming part of Letters Patent No. 624,954, dated May 16, 1899.

Application filed September 27, 1898. Serial No. 692,035. (No model.)

To all whom it may concern:

Be it known that I, CHARLES MARTIN MALLORY, a citizen of the United States, residing at Flandreau, in the county of Moody and 5 State of South Dakota, have invented a new and useful Improvement in Wire-Stitching Machines, of which the following is a specification.

My invention relates to improvements in 10 wire-stitching machines in which an inverting staple former, conveyer, and driver pivoted to an oscillating arm comprise the principal working parts; and the objects of my invention are, first, to provide a machine of simplified construction in which staples for stitching or binding are formed and used in a continuous manner, wire being fed into the machine from spools (by a device not shown); 15 second, to provide a machine that will not clog, and, third, to afford plenty of room for handling books, pamphlets, &c., between the staple-driver above and the table beneath. I attain these objects by the mechanism illustrated in the accompanying drawings, in 20 which—

Figure 1 is a side view, and Fig. 2 is a front view, of the entire machine. Fig. 3 is a sectional view of the former, conveyer, and driver, showing how staples are formed on the upward stroke; and Fig. 4 shows how they are 25 set into work and clenched beneath. Figs. 5 and 6 show the manner in which staple-former *a* and driver *d* are adapted to fit together.

Similar letters refer to similar parts throughout the several views.

The former *a* is milled or grooved to slide upon the driver *d*, the latter being slotted to receive a coil-spring, which holds the former *a* in proper position by a spring acting against 30 a pin set into the former. The latter is held from sliding off the driver *d* by the pin extending from former *a* into and through the slot of driver *d*. The former and driver thus 35 fixed together are held pivoted in side arm *L* by a rivet or pin passing through the hole in gear or toothed head of the driver *d*, as shown.

The main casting, with table *X* and oscillating arm *L*, constitutes the framework of the machine, while the wire-cutter *H*, toothed 40 rod *R*, the inverting staple former and conveyer *a*, with the staple-driver *d*, pivoted to 45 and operated in conjunction with the oscillat-

ing arm *L*, comprise the principal working parts of the machine.

Stapling-wire is fed into the machine from 55 the right-hand side, as shown in Fig. 2 by dotted line *P*, through a small hole *P'* in shear-lug *m*. (Shown in Fig. 1.)

The length of staples is regulated by the slide-stop *S* and the adjustable shear-slide *m*, 60 which are held to place by screws, as shown. The wire in entering the shear slide or lug *m* passes through to stop *S* just in front of the anvil or fixed internal staple-former *n*, over which the staple is formed by the external 65 former *a* on the upward stroke of arm *L*. In throwing the lever upward the former *a* is inverted with staple-driver *d* by the action of the toothed rack-rod *R* in conjunction with the geared or toothed head of the driver to 70 where it is held firmly in position upon the notch *J* of the arm *L* by coil-springs upon the rack-rod *R* in proper position for forming the staple. Just as the former *a* presses the wire on the anvil or internal former *n* the wire is 75 cut off by the shear *h*, which is operated by the pins *i*, Figs. 1 and 2. The staple is then formed and carried down in former *a* until the latter strikes the pamphlet or book *Y*, as shown in Fig. 4, where the continued downward movement of the staple-driver *d* forces it out of the former *a* through pamphlet to die *C*, where the ends of staple are clenched, as shown at *P*, Fig. 4.

The coil-springs on rack-rod *R* hold the 85 former *a* in position at either end of stroke, one spring acting on the upward and the other on the downward stroke when either forming or driving staples. The springs act alternately on either side of the lug on main casting through which the rack-rod *R* passes. 90 (Shown in Figs. 1 and 2.)

Having thus fully described my invention, I claim as new and desire to secure by Letters Patent—

1. The combination in a wire-stitching machine of the staple-former *a* and the staple-driver *d* provided with a toothed pivot end, a slot and coil-spring the rack-rod *R* provided with coil-springs, the oscillating arm *L* to 100 which driver *d* carrying former *a* is pivoted for the purpose specified and substantially as shown.

2. The combination in a wire-stitching ma-

chine of the rack-rod R, oscillating arm L, staple-driver d, provided with gear or toothed end, the former a, and the anvil n, substantially as shown and for the purpose specified.

5 3. The combination with the rack-rod R, oscillating arm L, staple-driver d, provided with the gear or toothed end, former a, and

anvil n; of the shear h, shear-lug m, and stop S, substantially as shown and for the purpose specified.

CHARLES MARTIN MALLORY.
